DESIGN FOR A GLOVE

Application filed November 2, 1929. Serial No. 33,274. Term of patent 3½ years.

To all whom it may concern:

Be it known that I, SUZANNE BALOUZET-TILLARD, a citizen of the Republic of France, and residing at 11 Rue de la Boetie, Paris, France, have invented a new, original, and ornamental Design for Gloves, of which the following is a specification, reference being had to the accompanying drawing, forming a part thereof and in which—

Figs. 1 and 2 are plan views respectively of the front and back of a glove, with the cuff extended, showing my new design; and

Figs. 3 and 4 are also plan views respectively of the front and back of the glove shown in Figs. 1 and 2, with the cuff turned over, showing my new design, the stippling in all four figures of the drawing indicating that a different color of material is used.

I claim:

The ornamental design for a glove, substantially as shown and described.

Signed at Paris, France, this 8th day of October, 1929.

SUZANNE BALOUZET-TILLARD.
